UNITED STATES PATENT OFFICE

HENRY J. LUFF AND WILLARD J. LUFF, OF CLEVELAND HEIGHTS, OHIO; SAID HENRY J. LUFF ASSIGNOR TO SAID WILLARD J. LUFF

FLOOR DRAIN

Application filed February 16, 1929, Serial No. 340,426. Renewed June 16, 1931.

The present invention relates, as indicated, to a floor drain, and more particularly to a valved and trapped drain. The primary object of the invention is to provide an effective drain of the type indicated. A further object of the invention is to provide means for preventing large particles of solid material from entering the trap. A further object of the invention is to provide means of the type last mentioned which may be reversed to prevent any flow into or from the trap. A further object of the invention is to provide means for preventing silt from entering the trap while permitting complete drainage of liquid from the basin into the trap. A further object of the invention is to provide an improved float valve for a trap of the class described, said valve being adapted to prevent backflow but also, and particularly, to allow free outflow of all quantities of water from the least up to the full capacity of the drain, and to provide a mechanical seal which will become effective before the sealing liquid has entirely evaporated from the trap in long periods of disuse, thereby reducing such evaporation, and which will also act by itself to prevent entrance of sewer gas in the absence of a liquid seal. Other objects of the invention will appear as the description proceeds. To the accomplishment of the foregoing and relates ends, said invention, then, consists of the means herein-after fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a plan view of the drain, a section of the perforated floor plate being broken away; Fig. 2 is a central vertical section through said drain on the line 2—2 of Fig. 1; Fig. 3 is a section taken substantially upon the line 3—3 of Fig. 2; Fig. 4 is a section taken substantially upon the line 4—4 of Fig. 2; Fig. 5 is a broken section similar to Fig. 2 illustrating another adjusted position

of one of the parts; Fig. 6 is a vertical section through one type of float adapted for use with the drain; and Fig. 7 is a view similar to Fig. 6 of another type of float.

Referring more particularly to the drawings it will be seen that the drain 10 comprises a conduit 11, preferably horizontal, formed to provide a trap 12 having an enlarged vertically disposed neck 13, the mouth thereof being internally threaded as at 14. The lower end of said neck is constricted into a throat 15, whereby a chamber 16, defined by said mouth 14 and said throat 15, is formed.

A cylindrical member 17 provided with a plurality of peripherally elongated apertures 18 in its cylindrical walls is formed with an open end 19 externally threaded as at 20 for engagement with the threads 14 of the mouth of the neck 13. It may here be mentioned that the aggregate area of the apertures 18 in the member 17 is at least equal to the cross-sectional area of the outlet of the trap, whereby full and free flow of liquid through the fitting is permitted. It will be readily understood that the primary reason for forming the apertures 18 in the cylindrical walls of the member 17, and for giving them a peripherally elongated form is to prevent the careless attempts to clean the trap by unskilled persons through the use of wires or sticks pushed down into the trap from above. A ring 21 of relatively soft metal is set into said end 19 to provide a seat for a float 22 later to be described in detail. Said float is vertically movable in said chamber 16 and is guided in its vertical movement by internally projecting guide ribs 23 most clearly illustrated in Figs. 2 and 3. These ribs maintain the float always in a central position with respect to the mouth of the neck, whereby flow

into the trap is evenly distributed over the surface of the float. Of course the result of this even distribution of flow is a self-cleansing action on the float. It will be seen from an inspection of Fig. 2 that, at the upper limit of its movement, the float 22 will close as a valve against the seat 21 on the member 17, and that at the lower limit of its movement, said float 22 will close as a valve against the walls 24 of the throat 15.

Referring to Fig. 2, three planes are shown, indicated as A, B and C. Plane A is the top flow level of the conduit 11, plane B is the bottom flow level and therefore represents 5 the normal water level in the trap 12, and plane C represents the lowest level at which a water seal will be maintained. It will be noted that the dip D of the trap is considerably below the bottom float seat 24, so 10 that when the trap is unused and the trap water level gradually lowers by evaporation the float 22 will seat on 24 while the water is yet well above the dip D, thus establishing a mechanical seal before the liquid seal is 15 lost. This mechanical seal also serves to hold the liquid seal longer because the evaporation is naturally fastest in the inner leg of the trap. As the water gradually evaporates away from beneath the float, the latter ceases 20 to have any part of its weight water-borne and so settles more firmly on the seat 24.

Referring now to Fig. 3, the construction of the float chamber there shown is a practical one from the foundry standpoint. It is 25 of course advantageous to have the guide ribs 23 cast integral with the rest of the trap but this presents a problem of making an arrangement whereby the cores can be drawn, and also such that any flash at the parting will 30 not interfere with the float rise and fall. Machining off inside flash is expensive, and to be avoided if possible. To these ends we have formed the ribs 23 by inward corrugations of the neck 13, these ribs having their 35 opposite faces, as E, E and F, F substantially parallel, but actually diverging inwardly just sufficiently to allow the cores to be drawn. In good foundry practice this spread would be about one-sixteenth of an inch to the foot. 40 In such a construction the partings will be at the intersection of the plane 2-2, Fig. 3 with the channel wall, in line with the parting in the rest of the casting.

The depth of the ribs is sufficient to leave 45 four channels around the float, the depth of each channel being such that the parting flash will not intrude upon the float path. The combined cross sectional area of these 50 four channels is somewhat greater than that of the conduit 11, so as to allow for friction and yet allow water flow past the float to the full capacity of the conduit 11 when the float is clear of both seats.

At its end opposite the end 19, the member 17 is formed as a solid plug 25 formed 55 with external threads 26 engageable with the threads 14. As is shown in Fig. 5, said member 17 may be removed from the location illustrated in Fig. 2, inverted, and screwed into 60 the mouth of the neck 13 in the position illustrated in Fig. 5 to close said mouth positively against flow through the trap into the basin 29 from the trap 12. Said end 25 is formed with a plurality of ears 27 to facilitate 65 rotation of said member 17. Said mem-

ber 17 is further provided with a plurality of radially extending lugs 28 adjacent its end 19 for a purpose later to be described.

As is clearly shown in Fig. 2, the drain 10 is formed to provide a basin 29, the open upper end of which is adapted to be covered by a perforated plate 30 provided with radial lugs 31 adapted to be engaged in an annular groove 32 through slots 33 in the well known manner. Within said basin 29 there is a 70 ring 34 centered upon the lugs 28 of the member 17. Said ring is formed with a sharply beveled lower edge 35 which rests upon the floor of the chamber 29. As will be apparent, any silt which enters the chamber 29 will be arrested by the ring 34. The drain unit is a casting, and consequently the floor of the basin 29 is not absolutely smooth. As a result, tiny openings will be present 75 between the edge 35 of the ring 34 and said floor, and these openings will permit the seepage of liquid past said ring, though they do not permit the passage of solid material.

As is shown in Figs. 1 and 2, the conduit 11 is formed with an internally threaded clean-out opening 36 which is normally closed by a plug 37.

In Fig. 6 we have shown on an enlarged scale a section through one type of float 22 which may be used in the present drain. 95 This float comprises a substantially hemispherical member 38. In the manufacture of the float, an internal bead 39 is formed adjacent the open end of said member 38 and a rigid disc 40 is entered into said member and located in contact with the outer edge of said bead. A dished member 41 having a concavo-convex nub 42 at its center is then placed in engagement with the outer face of the disc 40, and the projecting end 44 of that portion 43 of the member 38 which extends beyond the bead 39 is bent over into engagement with the rim of the member 41 to hold the same in place. It will be seen that this construction provides a float, the center of gravity of which is so located that such float will always present its hemispherical surface above the surface of a liquid in which it is 100 floating.

In Fig. 7 we have illustrated a second type 110 of float 22' which may be preferably formed of bakelite or similar material. This float comprises a substantially hemispherical member 45 having a thickened portion 46 adjacent its open end. Said portion 46 is internally notched as at 47 for the reception of a dished member 48 also of bakelite or similar material having a concavo-convex nub 49 at its center. The member 48 may be cemented in place in the notch 47, and this construction likewise provides a float which will always present its hemispherical surface above the surface of a liquid in which it is 115 floating.

Other modes of applying the principle of 130

our invention may be employed instead of the one explained, change being made as regards the mechanism herein disclosed, provided the means stated by any of the following claims or the equivalent of such stated means be employed.

We therefore particularly point out and distinctly claim as our invention:

1. In combination with a floor drain trap having an inlet basin provided with a port in its bottom, a cylindrical strainer having its open end engaged in said port, a plurality of radial lugs on said strainer, and means centered on said lugs for arresting silt and the like before it reaches said strainer, while permitting complete drainage of liquid from said basin.

2. In combination with a floor drain trap having an inlet basin provided with a port in its bottom, a cylindrical strainer having its open end engaged in said port, a plurality of radial lugs on said strainer, and an annular collar centered on said lugs.

3. In combination with a floor drain trap having an inlet basin provided with a port in its bottom, a cylindrical strainer having its open end engaged in said port, a plurality of radial lugs on said strainer, and an annular collar centered on said lugs and having a bevelled edge resting on the floor of said basin.

4. As an article of manufacture, a cylindrical strainer having an open end and a closed end, said open end being adapted to serve as a seat for a float, the cylindrical wall of said strainer being pierced by a plurality of horizontal elongated apertures, the opposite ends of said strainer being threaded to hold said strainer in place against back pressure.

5. A floor drain having in combination an inlet basin, a port in the bottom of said basin, a vertical float chamber below said port, a float therein, a water seal trap below said float chamber, an open-bottomed strainer having its bottom engaged in said port, an annular collar positioned around said port by means of said strainer, the bottom of said strainer comprising the top seat for said float above the normal water level of said trap, an enlarged portion of the inner arm of said trap forming the bottom seat for said float, said bottom seat being below the normal but above the minimum trap water level.

6. A floor drain comprising a trap, a float and a vertically disposed float chamber associated with the inlet portion of said trap, said float chamber having a valve seat at both its upper and lower ends, said chamber being formed with its upper end spaced above the top of the float at normal water level in said trap and its lower end spaced below the normal water level but above the lowest water level in said trap, said chamber having a series of vertically disposed guides adapted to position a float centrally in said chamber

at any level between said upper and lower valve seats, or upon either of said seats.

7. A floor drain fitting comprising a horizontal pipe, a trap integral therewith and a float valve above said trap, said valve comprising a seat formed in the inner arm of the trap immediately above the dip of the trap, a float adapted to close against said seat, an upper seat reversely positioned to said lower seat and adapted to be closed by said float in its upper movement, said lower seat being below the overflow level of said fitting and said upper seat being above the normal flow level of said fitting, whereby an open passage for liquid exists at normal liquid level.

8. A floor drain having a horizontally disposed outlet conduit, a basin having its top above the top of said conduit and its bottom outlet below the top of but above the bottom of said conduit, a trap connecting said conduit with said basin, the inner leg of said trap forming a float chamber below said basin, a float in said chamber, float seals in the basin bottom outlet at a distance above the dip of the normal trap water level and below the float above the minimum trap water level, the wall of said float chamber being formed with a plurality of axially directed corrugations the inner edges of which constitute float guides, the combined cross-sectional area of the channels between said corrugations being not less than the cross-sectional area of said conduit.

9. In a cast floor drain trap fitting having an inner vertical leg, a float chamber in said leg, vertical guide ribs in said chamber, seats in said chamber above and below said guide ribs and channels between said ribs, each of said ribs being formed with all faces disposed to intercept perpendicularly from a central vertical plane through said fitting.

Signed by us this 5th day of February, 1929.
